UNITED STATES PATENT OFFICE.

WILLIAM A. JOHNSON, OF YONKERS, NEW YORK, ASSIGNOR OF ONE-THIRD TO
BARTON K. BUCKNAM, OF WHITE PLAINS, NEW YORK, AND ONE-THIRD TO
RICHARD L. BUCKNAM, OF NEW YORK, N. Y.

PICTURE-FILM REEL.

1,412,005.

Specification of Letters Patent.

Patented Apr. 4, 1922.

Application filed July 9, 1920. Serial No. 395,007.

To all whom it may concern:

Be it known that I, WILLIAM A. JOHNSON, a citizen of the United States, and a resident of Yonkers, Westchester County, and 5 State of New York, have invented certain new and useful Improvements in Picture-Film Reels, of which the following is a specification.

My present invention is a reel for moving 10 picture films and the like, and the objects of the invention are to provide a simple and practical construction, which will enable the film to be removed bodily from the reel without the necessity of unwinding the same and, 15 conversely, which will permit of the film being applied in coiled form to the reel and without the necessity for winding the same thereon.

The invention involves a number of novel 20 features of construction, combinations and arrangements of parts, as will be herein-after described in detail.

In the drawing accompanying and forming 25 a part of this specification, I have illustrated the invention embodied in one of its most simple forms, but wish it understood that variations may be made in the structure without departure from the true spirit and scope of the invention as herein defined 30 and claimed.

In the drawing referred to:

Figure 1 is an edge and partial sectional view of the reel.

Figure 2 is an end elevation of the reel 35 from the end having the removable flange or head.

Figure 3 is an enlarged broken sectional view, similar to the upper portion of Figure 1 and showing the removable flange as released from the supporting hub.

Figure 4 is a broken detail and partly sectional view, illustrating one of the uses to which the invention is particularly adapted, that is, to a projecting machine in which 45 the film is unwound from the center of the coil.

In the construction illustrated, the reel is made up with a relatively fixed flange or head 5 and a removable flange 6. The hub portion which connects these two heads or flanges consists of a series of spring fingers 7 fastened at 8 to an annular supporting rib 9 on the fixed reel head 5. These spring

fingers, which all may be cut from a single continuous strip 10 of spring metal, are 55 bent or biased radially inward and are provided at their free ends with openings or perforations 11 to receive inwardly projecting tangs or lugs 12 on the removable flange 6. 60

The free ends of the spring fingers are thrust outwardly into holding engagement with the lugs of the removable reel head by a spreading ring 13 located within the hub and carried by a disc 14, which is fixed to the hollow spindle 15 of the reel. This spindle carries at its outer end a head or flange 16 by which the spindle may be operated either to expand or to retract the flange holding spring fingers. This operating head 16 is shown as adapted to be secured by the turn buttons 17 pivoted on the fixed reel flange 18 and adapted to be turned, as shown in Figures 1 and 2, into position overlapping the head 16 of the spindle. 75

In the first two figures I have shown the spindle as forced inwardly and secured to hold the spring fingers in locking engagement with the removable reel flange. In this condition the reel may be used in the 80 customary fashion to wind the film thereon, it being ordinarily provided with one or more of the customary clips for holding the leading end of the film.

When it is desired to remove the coiled 85 film from the reel it is only necessary to swing the turn buttons, as indicated in Figure 3, and to shift the spindle so as to permit the flange securing fingers to contract. The retractive movement of the expanding 90 ring or spreader 13 may be easily accomplished by pressing on the end of the spindle 15 or on the web or disc 14 which carries the expanding ring. When the spring securing fingers are thus contracted, the reel flange 95 is free to be removed and this enables the film to be removed from the reel in its coiled condition.

The reel is reassembled by simply dropping the removable flange over the ends of 100 the spring fingers and then forcing the spindle inward to cause the spreader to expand the spring fingers into locking engagement with the radially projecting lugs of the removable flange. 105

The invention is particularly useful in

connection with machines of the type disclosed in Patent No. 1,116,580, where, as I have here illustrated in Figure 4, the coil of film 20 is supported on a rotatable receiver 21 and the coil is unwound from the center outward and fed through the projector mechanism of the machine. In placing the film in such a machine it is possible with my invention to simply push the reel down over the rotatable receiver which automatically contracts the spring holding fingers so as to free the removable flange and to drop the same, with the coil of film, down onto the rotatable receiver and therefore in position to be used in the machine.

What I claim is:

1. A reel of the character described, having a removable flange and provided with spring fingers for securing the flange in position and means on the reel for simultaneously shifting said spring fingers to secure or to release the removable flange.

2. A reel for moving picture film having a hub provided with radially shiftable fingers, a removable flange engageable by said fingers and means on the reel for producing engagement and disengagement of said fingers with respect to the removable flange.

3. A reel having a fixed and a removable flange, a series of substantially circularly arranged spring fingers carried by the fixed flange, said spring fingers and the removable flange having interlocking parts and a shiftable ring on the fixed flange for controlling engagement and disengagement of the spring fingers with respect to the removable flange.

4. A reel having a fixed and a removable flange, a series of substantially circularly arranged spring fingers carried by the fixed flange, said spring fingers and the removable flange having interlocking parts and a spreader on the fixed flange for expanding the spring fingers into interlocking engagement with the removable flange.

5. A reel having a fixed and a removable flange, a series of substantially circularly arranged spring fingers carried by the fixed flange, said spring fingers and the removable flange having interlocking parts, a spreader on the fixed flange for expanding the spring fingers into interlocking engagement with the removable flange and means for securing the spreader in adjusted position.

6. A reel having a removable flange provided with radially projecting lugs, spring fingers provided with perforations to receive said lugs and biased to normally disengage the same and a spreader for flexing the spring fingers into holding engagement with the lugs.

7. A reel comprising relatively fixed and removable flanges, an axially shiftable spindle carried by the fixed flange, holding fingers for the removable flange mounted on the

fixed flange and operating means for shifting said holding fingers carried by the shiftable spindle.

8. A reel comprising relatively fixed and removable flanges, an axially shiftable spindle carried by the fixed flange, a substantially circularly arranged series of spring fingers carried by the fixed flange and arranged to be expanded into holding engagement with the removable flange and a spreader for expanding said fingers carried by the shiftable spindle.

9. A reel comprising relatively fixed and removable flanges, an axially shiftable spindle carried by the fixed flange, a substantially circularly arranged series of spring fingers carried by the fixed flange and arranged to be expanded into holding engagement with the removable flange, a spreader for expanding said fingers carried by the shiftable spindle and means for securing the spindle in adjusted relation.

10. A reel comprising relatively fixed and removable flanges, an axially shiftable spindle carried by the fixed flange, a substantially circularly arranged series of spring fingers carried by the fixed flange and arranged to be expanded into holding engagement with the removable flange, a spreader for expanding said fingers carried by the shiftable spindle, means for securing the spindle in adjusted relation and consisting of an exposed head on the spindle and a turn button on the fixed flange for engagement with said head.

11. A reel comprising relatively fixed and removable flanges, a shiftable spindle carried by the fixed flange, inwardly biased spring fingers carried by the fixed flange and provided with perforated ends, the removable flange having inwardly projecting lugs for engagement in said perforations and a spreader for expanding the spring fingers carried by the shiftable spindle.

12. A reel comprising flanges, one removable from the other, contracting spring fingers carried by one flange and expandable into holding engagement with the other flange and shiftable means carried by one of the flanges for expanding the spring fingers into holding engagement with the flange.

13. A reel of the character described, having a removable flange and provided with spring fingers for securing the flange in position and means on the reel engageable with the fingers for simultaneously shifting said spring fingers to secure or to release the removable flange.

14. A reel having a fixed and a removable flange, a series of substantially circularly arranged spring fingers carried by the fixed flange and adapted to extend through the removable flange, said spring fingers and the removable flange having in-

terlocking parts and a shiftable ring on the fixed flange for controlling engagement and disengagement of the spring fingers with respect to the removable flange.

5 15. A reel for moving picture films having a hub provided with radially shiftable fingers, a removable flange engageable by said fingers and axially movable means on the reel for producing engagement and dis-
10 engagement of said fingers with respect to the removable flange.

16. A reel having a fixed and a removable flange, one of said flanges having spring fingers adapted to engage the other flange
15 and means on the reel for simultaneously shifting said fingers to secure or release the flange.

17. A reel having a pair of flanges, a hub carried by one flange, spring fingers carried by the hub and engageable with the other 20 flange and means for simultaneously shifting said fingers to engage or release the second flange.

18. A reel having a pair of flanges, a hub carried by one flange, spring fingers carried by the hub and engageable with the other flange and means positioned within the hub for simultaneously shifting said fingers to engage or release the second flange. 30

In witness whereof, I have hereunto set my hand this 8th day of July, 1920.

WILLIAM A. JOHNSON.
